UNITED STATES PATENT OFFICE

113,644

DESIGN FOR A SHOE

Ben Weiner, Lewiston, Maine

Application December 16, 1938, Serial No. 81,815

Term of patent 3½ years

To all whom it may concern:

Be it known that I, Ben Weiner, a citizen of the United States and a resident of Lewiston, in the State of Maine, have invented a new, original, and ornamental Design for Shoes, of which the following is a specification, reference being had to the accompanying drawing, forming part thereof.

I claim:

The ornamental design for a shoe, substantially as shown.

BEN WEINER.
